(57) **CLAIM**

The ornamental design for a golf club head, as shown and described.

DESCRIPTION

FIG. 1 is a front, left side, perspective view of a golf club head, showing my new design;

FIG. 2 is a bottom right front perspective front view thereof;

FIG. 3 is a back side elevation view thereof;

FIG. 4 is a front side elevation view thereof;

FIG. 5 is a left side elevation view thereof;

FIG. 6 is a right side elevation view thereof; and

FIG. 7 is a top plan view thereof; and,

FIG. 8 is a bottom plan view thereof.

The curved broken lines shown on the hosel portion indicate variable length. The broken lines on the drawing figures form no part of the claimed design. Portions of the claimed design are shown separated and bound by a bracket to indicate indeterminate length and that forms no part of the claimed design.
